UNITED STATES PATENT OFFICE.

ISAAC P. TURNER, OF TROY, NEW YORK, ASSIGNOR TO GEORGE W. PINE,
OF SAME PLACE.

STAYING-PIECE FOR GARMENT SLIT-OPENINGS.

SPECIFICATION forming part of Letters Patent No. 295,959, dated April 1, 1884.

Application filed November 23, 1883. (No model.)

To all whom it may concern:

Be it known that I, ISAAC P. TURNER, of the city of Troy, county of Rensselaer, and State of New York, have invented a new and 5 useful Improvement in Staying-Pieces for Garment Slit-Openings, of which the following is a specification.

My invention relates to the staying-pieces that are applied to the slit-openings of garments to produce a button-fly lap, and more 10 particularly to such of them as are used in connection with the back and sleeve side openings of shirts.

Accompanying this specification, and forming 15 a part of it, are five plates of drawings containing seven figures, illustrating my invention as applied to the back-opening of shirts, with the same designation of parts by letter reference used in all of them, of which—

20 Figure 1 shows the form and manner of cutting and folding the two plackets or pieces employed to make a staying-piece and button-fly-lap. Fig. 2 illustrates the two plackets or pieces, with the stay-flaps cut in adjacent 25 sides of each and laid one over the other, folded transversely and sewed transversely, and the annex figure A' indicating a section taken on the line $x^1 x^1$ of Fig. 2, and the annex A² a section taken on the line $x^2 x^2$ of Fig. 2.

30 Fig. 3 illustrates the position of the parts after having been sewed, as indicated at Fig. 2, and then with one of the pieces folded over and down on the line S' of their transverse union, the outer ends of the pieces being 35 shown as cut away to reduce the size of the illustration. The annex figure B shows a section made transversely on the line $x^3 x^3$ of said Fig. 3. Fig. 4 shows the parts after they have been sewed and transversely folded, as 40 illustrated in Fig. 3, and then with one of the parts folded longitudinally over their transverse line of union. The annex figure C' indicates a longitudinal section taken on the line $x^4 x^4$, and the annex figure C² designates a 45 cross-section taken on the line $x^5 x^5$ of Fig. 4. Fig. 5 illustrates the position of the two pieces after having been placed as indicated at Fig. 4, and with one of them folded longitudinally; and the annex figure D designates a section of 50 the parts taken on the line $x^6 x^6$ of said Fig. 5.

Fig. 6 illustrates the completed union of the parts, and as when ready for attachment to the sides of the shirt opening or slit, and the annex figure E indicates a section of the parts taken on the line $x^7 x^7$ of said Fig. 6. Fig. 7 55 illustrates the united pieces attached to the back opening of a shirt. In all the illustrations by sections the thickness of the parts is exaggerated to better show them.

The parts as cut, folded, and shaped are 60 designated by letter reference, and the process steps by which they are connected and then attached to the shirt are described as follows: The letters F' F² indicate two pieces or plackets of fabric having a rectilinear form, each 65 one of which is made wide enough and long enough, when connected, to produce the outer and inner facing of the overlap and the underlap, and intermediately a stay for the end of the slit and a facing for each side of the garment below the slit. The outer edges on the opposite sides of each piece are made with the oppositely turned-in edges $a' a^2$, and one of the plackets or pieces creased with the fold lines O' and O² and the other with the fold- 70 lines O³ and O⁴. A vertical slit, b, is made and cut upwardly in each part or placket at its lower end, to produce in each the flap i, that unitedly form, when the two are laid with one above the other, transversely folded, and 75 then transversely sewed, a crotch or slit-stay, and the two plackets or pieces thus cut and fold-creased are united, and then attached to the shirt in the following manner: The parts F' and F² are laid to lap on one another on 80 the lines of the slits b b made in each. The two flaps i i are then together turned up and folded down transversely, and then transversely sewed at S', as indicated at Fig. 2 and its annex sections. After the latter attach- 85 ment has been made, the two plackets or parts are turned over and down on the line of their transverse union at S', as shown at Fig. 3, and while in this position the part F' is folded over longitudinally inwardly on the fold line 90 O⁴, so that the latter is parallel with and over the fold-line O² of the placket or piece F², said fold being made also through the edges of the doubled stay-flaps i, and with the parts 95 in the position as indicated at Fig. 4. When 100

this step in the process has been done, the placket or piece F' , which was folded over and down transversely on the line of the seam S' , is folded back on the latter, so that the 5 upper ends of the two pieces are again parallel. Then the said piece F' is longitudinally folded on the fold-line O^3 and reversely folded on the fold-line O^4 , so that the turned-in edge a' of said placket or piece is parallel with the 10 fold-line O^3 , and with the parts appearing as illustrated at Fig. 5. The piece F^2 is then longitudinally folded back on itself in the same manner as was the piece F' , with the turned-in edge a' parallel with the fold-line 15 O^3 of said piece, said fold taking in the adjacent edges of the stay-flaps i . The parts thus placed are then, in succession, sewed on their opposite edges, as indicated at S^2 and S^3 of Fig. 6, when the strip, as made and shown 20 at Fig. 6, is ready for attachment to the garment, and this is done in the following manner: One side of the garment slit-opening, D' , is inserted in the opening I' of the folded placket F^2 , and the other side of the garment- 25 slit, D^2 , is inserted within the opening I^2 of the folded placket F' , and the open edges of each part sewed with an edge of the slit-opening thus intermediately placed, and the subtending ends d of each strip sewed so as to include 30 intermediately the garment below the slit, with the parts appearing as shown at Fig. 7.

As this class of attachments to garment-slits have heretofore been made of variously-modified forms of continuous strip, and from rectilinear plackets or pieces with entrant folds to receive the sides of slit-opening, without any additional staying means at the bottom of the slit other than that of the strip itself, 35 40 which forms the fly and facing for the underlap, they were deficient in strength where the latter was most required. By my improvement and the addition of an interiorly-placed staying part, which is out of sight, I materi-

ally increase the strength of the parts, and at 45 the same time secure the exterior desirable continuity of finish.

Having thus described my invention, what I claim, and desire to secure by Letters Patent, is—

1. In a staying-piece for garment slit-openings, the combination of the rectilinear plackets or pieces F' and F^2 , each made with two equidistantly-arranged longitudinal fold-lines and with oppositely turned-in side edges, the 55 vertically-separated stay-flaps i , cut in each of said plackets or pieces, the transverse seam S' , centrally uniting said stay-flaps when laid one over the other and folded transversely, a crotch-fold made in said united stay-flaps on the line 60 of their transverse union, and the stitching S' and S^2 , separately uniting oppositely at one side the coincident edges of each of said plackets or pieces after each has on its longitudinal fold-lines been folded back on itself to 65 include the edges of the transversely-united stay-flaps, as shown and described.

2. The combination, with a garment slit-opening, of the rectilinear plackets or pieces F' F^2 , each cut to have the blank-form stay-flaps i , the transverse seam S' , centrally uniting said flaps when laid one over the other, folded over and down to be doubled transversely, a crotch-fold made in said united stay-flaps transversely and in the line of their 70 75 sewed union, and the said plackets or pieces folded longitudinally to include and cover the edges of said united stay-flaps, and each attach to one of the sides of the garment slit-opening, as herein shown and described.

Signed at Troy, N. Y., this 20th day of November, 1883.

ISAAC P. TURNER.
